UNITED STATES PATENT OFFICE.

SAMUEL L. FISHER, OF BUTLER, PENNSYLVANIA.

COLLAPSIBLE FURNITURE.

1,331,145.

Specification of Letters Patent. Patented Feb. 17, 1920.

Application filed November 10, 1917, Serial No. 201,327. Renewed December 31, 1919. Serial No. 348,543.

To all whom it may concern:

Be it known that I, SAMUEL L. FISHER, a citizen of the United States, residing at Butler, in the county of Butler and State of Pennsylvania, have invented new and useful Improvements in Collapsible Furniture, of which the following is a specification.

This invention relates to collapsible furniture and more particularly to a collapsible chair and has for its primary object to construct a chair of this character which when set up will have the strength and rigidity of a non-collapsible chair.

An object of the invention is the novel manner of connecting the different parts so that the same will take up a minimum amount of space when collapsed for shipment.

Besides the above my invention is distinguished in the manner of locking the parts and effectively holding the parts against independent vibration.

With these and other objects in view the invention will be better understood from the following detailed description taken in connection with the accompanying drawings wherein:

Figure 1 is a side elevation of the chair. Fig. 2 is a front elevation.

Fig. 3 is a plan view showing the parts collapsed.

Figs. 4, 5 and 6 are detailed views of the hinge connection between the parts of the back.

Figs. 7 and 8 are detailed views of the detachable connection between the uprights and arms.

Figs. 9 and 10 are detailed views of the back.

Figs. 11 and 12 are detailed views of the brace.

Fig. 13 is another view of the chair when collapsed.

Fig. 14 is a detailed view of the strut.

Again referring to the drawings the numeral 1 designates the back of the chair consisting of two parts, an upper part 2 and a lower part 3 hinged together as indicated at 4 while the lower part is provided with a pin 5 adapted to enter a recess 6 in the upper part when the parts are assembled.

Passing through each part 2 is a bolt or pin 7 pivotally connecting the bottom 8 with the back in a manner to allow the bottom to swing toward and lay parallel to the

back as clearly shown in Fig. 3. Also hingedly connected to the back as indicated at 9 are arms 10 each provided with a recess 11 partly closed by a plate 12. With the plate 12 of each arm operates a clip 13 on the upper end of an upright 14, which is also pivoted to the forward part of the bottom as indicated at 16, so that the uprights may swing into the proper position to lie parallel to one edge of the bottom and also to the back 1.

Swingingly connected to the bar 17, that connects the lower parts of the uprights together, is the threaded rod 18 of a strut 19, the nut 20 of which has one end pointed so as to be inserted into a recess 21 in the connecting bar 22 of the back. By this arrangement it will be seen that by adjusting the nut on the rod 18 the back and upright 75 are forced away from each other with the result that the clip is prevented from moving out of engagement with the plate 12. Thus it will be seen that upon simple adjustment of the nut 20 all parts are locked 80 against movement.

If found an advantage in practice a brace 23 may be utilized. This brace has a slotted connection 24 with the rod 18 and a pivotal connection with the seat or bottom as 85 indicated at 25. Owing to the respective position of the brace and rod 18 a binding action is accomplished between the rod and walls of the slot 24 when the brace is forced in a direction indicated by the arrow. 90

It is to be understood that the structural embodiment of the invention as a whole and its various features as shown are merely illustrative and not restrictive, since I am well aware that many of the details of construction can be widely varied without departing from the spirit of the invention. I therefore do not desire to be limited in these particulars or in any others, except as set forth in the appended claims. 95

Having described my invention what I claim is:

1. A collapsible chair comprising a two part back hinged together, a bottom hinged to the back, arms and uprights hinged respectively to the back and bottom and having a detachable connection with each other, and means for locking the heretofore mentioned parts against movement when the chair is assembled. 105

2. A collapsible chair comprising a two piece back hinged together, arms hinged to

the back, a bottom hinged to the back, uprights hinged to the bottom and having a lock engagement with the arms, and adjustable means associated with the bottom, back 5 and upright for holding the same against movement.

3. A collapsible chair comprising a two part back hinged together, a bottom hinged thereto, arms hinged to the back, uprights 10 pivotally connected to the bottom and having a lock engagement with the arms when the uprights are forced in a predetermined direction and an adjustable element for moving the upright in said predetermined 15 direction.

4. A collapsible chair comprising a two part back hinged together, a bottom hinged thereto, arms hinged to the back, uprights pivotally connected to the bottom and hav-

ing a lock engagement with the arms when 20 the uprights are forced in a predetermined direction, an adjustable element for moving the upright in said predetermined direction and a brace having a swinging connection with the bottom and a cam action with said 25 element.

5. A collapsible chair comprising a back composed of two parts hinged together, a bottom hinged to the back, arms hinged to the back, uprights having a connection with 30 the bottom and with the arms, an adjustable strut mounted between the back and uprights and a brace pivotally connected to the bottom and having frictional engagement with the strut.

In testimony whereof I affix my signature.

SAMUEL L. FISHER.
